J. E. BRITTAI

DISK SHARPENING MACHINE

Filed July 26, 1921

INVENTOR

John E. Brittain
BY
George W. Hinton
ATTY.

UNITED STATES PATENT OFFICE.

JOHN E. BRITTAI, OF GUILFORD, MISSOURI.

DISK-SHARPENING MACHINE.

Application filed July 26, 1921. Serial No. 487,789.

To all whom it may concern:

Be it known that I, JOHN E. BRITTAI, a citizen of the United States, residing at Guilford, in the county of Nodaway and 5 State of Missouri, have invented certain new and useful Improvements in Disk-Sharp- ening Machines, of which the following is a specification, reference being had therein to the accompanying drawing.

10 My invention relates to improvements in that class of machines, which are used for sharpening the disks of agricultural implements, and the objects of my improvements are, first; to provide a simple, substantial and durable machine of this class, by the use of which the edges of disks are evenly ground, at any predetermined angle of inclination to the sides of the disks, and said edges are kept cool while being sharpened, second; to provide adjusting means, whereby the machine may be adjusted for sharpening disks of various diameters, third; to provide a machine of this character, which shall evenly grind the edges of disks, 25 which have been bent out of shape to a certain extent, by accident or from use, fourth; to provide stopping means, whereby the grinding of a disk is automatically stopped, after grinding a predetermined amount of 30 metal therefrom, fifth; to so arrange the driving means, that the grinding wheel and the disk are simultaneously rotated by the application thereto of one belt, sixth; to so shape and proportion the parts of the machine, that it can be securely mounted on either a specially constructed stand, or on an ordinary bench or table.

I attain these objects by the mechanism illustrated in the accompanying drawings, 40 in which:

Figure 1 is a front view of the disk sharpening machine, a portion of the pressing roller being broken away. Fig. 2 is a side view in detail, of the pressing roller and of 45 the limiting means. Fig. 3 is a top view of the machine, a portion of the disk being indicated by dot and dash lines. Fig. 4 is a top view in detail of the disk elevating means.

50 Referring to Fig. 1, the ways 1 are formed on the bed 2, of the machine, on which bed the grinding shaft 3 is rotatably mounted. The drive pulley 4 (see Fig. 3,) is secured on one end of said shaft, and the grinding wheel 5 is secured on the other end thereof.

55 The table 6 is slidably mounted on said

ways, and is secured at variously adjusted distances from the shaft 3, by the bolt and nut 7. The bearing brackets 8 and 9 are formed with said table, in the extremities 60 of which brackets, the disk shaft 10 is rotatably mounted.

The upper end portion 11, of said disk shaft 10, is formed square, transversely, on which portion the disk 12, of an agricultural implement is loosely mounted, for oscillation thereon. The channeled shifter collar 13 is secured on said disk shaft, with which collar, one end of the shifter fork 14 is engaged by the studs 15. The lever 16 is 70 formed with said shifter fork, which lever is oscillatably mounted on the screw 17, which is secured in the bracket 9. Said lever is secured at variously adjusted angles of inclination by the bolt 18, which is provided with the head 19 formed thereon, which head is tightly pressed against the adjacent edge portion of bracket 9, by the hand nut 20, which is screwed on said bolt against the front side of the lever 16. The 75 handle 21 is formed on the extremity of said lever, adjacent to said hand nut. Said parts form adjusting means, whereby the height of the shaft 10 and the thereon carried disk 12, are secured at variously adjusted heights.

The worm gear 22 is secured on the upper end portion of said shaft, and is in engagement with the worm 23, which latter is secured on one end of the worm shaft 24, 90 which worm shaft is rotatably mounted on said table 6. The pulley 25 is secured on the other end of said worm shaft, and is driven by the lower portion of the belt 26, which passes over the upper side said pulley, and beneath and around the drive pulley 4. Said belt passes therefrom, around the drive wheel 27, (see Fig. 1,) which is rotated by any suitably applied power, not shown.

Referring to Fig. 2, the pressing roller 28 is rotatably mounted on the stud shaft 29, one end portion of which is secured in the free end of the arm 30. The opposite end of said arm is oscillatably mounted on the stud bolt 31, which is secured in the upper end of the bracket 32, the lower end of which is formed with the bar 33. Said bar is slidably mounted on the bed 1, for sliding thereon, through the guides 34. The thumb screw 35 is screwed through an un-designated threaded aperture formed

through one of the guides 34, for pressing said bar against said bed.

Said bar is slidably adjusted, and is held in said adjustments by the last described parts, seen in Fig. 3.

The thumb wheel 36 is secured on the screw bolt 37, by which said bolt is screwed through an undesignated threaded aperture, formed through the extremity of the bracket 38. The other end of said bracket is formed with said bar 33. Said bolt is secured in various positions, as to height, by the lock nut 39.

The projection 40 is formed with the bracket 38, the extremity of which projection is directly beneath the extremity of the arm projection 41, which latter is formed on the arm 30.

The lower end of the spring 42 is connected with the extremity of the extension 40, and the upper end of said spring is connected with eye 43, (see Fig. 2,) which is formed on the lower end of the screw 44. Said screw is passed through an aperture formed through the extremity of the extension 41, and is secured at variously adjusted positions, as to height, by the thumb nut 45, which is screwed on said screw. Said parts form adjusting means, whereby the tension of said spring is adjusted, for adjusting the pressure of the roller 28, upon the disk 12, seen in Fig. 1.

In the operation of the described disk sharpener, with the parts in the position shown, the operator loosens the nut 7, and thereafter slides the table 6, to such position, that the thereby carried edge portion of the disk 12, is in the desired position, on the grinding wheel 5. He then tightens said nut, and thereafter loosens the hand nut 20. He then grasps the handle 21, and by it and the connecting parts, lifts the disk 12 to the desired elevation for placing its edge portion at the desired angle of inclination to the periphery of said grinding wheel, for grinding said edge portion to the desired angle of inclination to the sides of said disk, after which he tightens said hand nut.

Said operator loosens the lock nut 39 (see Fig. 2,) and by the thumb wheel 36 turns the bolt 37, until it is adjusted to the desired height for stopping downward movement of the adjacent edge portion of said disk, after which he tightens said lock nut.

Said operator then applies the unshown power to the drive wheel 27, (see Fig. 1,) which by the belt 26 rotates the pulleys 25 and 4 and their respectively connected shafts 24 and 4.

The worm shaft 24, by its worm gear connected parts, slowly rotates the disk 12, and the direct belt drive of the grinding wheel 5, rotates it at high speed, for grinding

said edge portion of the disk 12. Said edge portion of said disk is pressed downward upon said grinding wheel, by the spring actuated roller 28. When said edge portion of said disk reaches the upper end of the bolt 37, the downward movement of said edge portion of said disk is thereby stopped, after which it rides idly over said bolt, without being farther ground by said grinding wheel.

It will be understood that the automatically operated rotation of the disk 12, moves the portion thereof which is being ground, at a uniform speed over the grinding wheel 5, and the loose connection of said disk with the shaft 10, allows said disk to oscillate, to a certain extent, from action of said pressing wheel 28, thereby evenly grinding said edge portion of said disk, even though the same be bent to some extent out of true shape.

It will also be understood that the small amount of heat, generated in the edge portion of said disk by the friction of grinding the same is fully radiated therefrom into the air, along the far greater portion of said edge, which is not in contact with said grinding wheel.

After said disk is thus sharpened, it is removed from the machine, and is replaced by another disk, in the following manner:

Said operator, with one hand lifts the roller 28 from said disk, overcoming the spring 42, seen in Fig. 2, and with the other hand loosens the hand nut 20, (see Fig. 1,) after which, by the previously described disk lifting means, he lifts the shaft 10 and the thereon carried worm gear 22, until said gear is lifted from engagement with the worm 23, upon which said disk is no longer rotated by said worm, and said operator thereafter tightens said hand nut. He then lifts said disk 12 from the square portion 11 of said shaft 10 and lays it aside.

Said operator then replaces said removed disk with another disk to be ground as previously described, after which he loosens the hand nut 20, and by said disk lifting means, lowers said disk, to the position which was occupied by the sharpened disk.

It will be understood, that disks of various diameters can be so adjusted in position, relative to the grinding wheel 5, that their edges will thereby be ground to the proper bevel, for efficient sharpening of the same.

Having fully described my invention, what I claim as new and desire to secure by Letters Patent, is:

1. A base for supporting a grinding machine; a grinding wheel rotatably mounted on said base; a table mounted on said base for slidable movement from and toward said grinding wheel; securing means whereby said table is secured in its various positions; bearing brackets formed with and project-

ing from one of the edges of said table; a vertically disposed disk shaft rotatably mounted in the extremities of said brackets; worm gear driving means mounted on said 5 table and shaft whereby said disk shaft is slowly rotated; a square portion formed on the upper end of said shaft for receiving and loosely holding a disk thereon with the edge of said disk in contact with the peripheral surface of said grinding wheel; a rotatably mounted roller for pressing the contacted portion of the edge of said disk upon said grinding wheel; a spring for actuating said roller to press upon said disk; 10 and adjusting means whereby the tension of said spring is adjusted.

2. In a disk sharpening machine; a base for supporting said machine; a grinding wheel rotatably mounted on said base; a rotatably mounted disk shaft; a bar slidably mounted on said base for adjustment longitudinally; securing means whereby said bar is secured in its various adjustments; an upwardly extending arm formed on said bar; 15 an arm one end of which is oscillatably mounted on the upper end of said upwardly extending arm; a pressing roller rotatably mounted on the other end of said arm for pressing the edge of the disk on said grinding wheel; a spring carried by said arm and bar for pulling the free end portion of said arm downward; and adjusting means whereby the tension of said spring is adjusted.

3. In a disk sharpening machine; a base on which said machine is mounted; a table slidably mounted on said base; brackets formed on one edge of said table; a disk shaft rotatably mounted in the extremities 20 of said brackets; lifting means whereby said shaft is raised and lowered for adjustment as to height; securing means whereby said lifting means is secured in its various adjustments; and pressing means whereby the contacted portion of the edge of said disk is pressed downward upon said grinding wheel.

4. In a disk sharpening machine; a base on which said machine is mounted; a grinding wheel rotatably mounted on said base; a disk holding means on which a disk is loosely held with a portion of its edge in contact with said grinding wheel; a bar mounted for slidable adjustment on said base; securing means whereby said bar is secured in its various adjustments; a bracket formed on one end of said bar; a stop screw adjustably screwed through a threaded aperture formed through the extended end portion of said bracket for limiting downward movement of the adjacent edge portion of said disk; securing means whereby said stop screw is secured in its various adjustments; and pressing means whereby the contacted portion of the edge of said disk is pressed downward upon said grinding wheel.

5. In a disk sharpening machine; a base on which said machine is mounted; a grinding shaft rotatably mounted on said base; a grinding wheel secured on one end of said shaft; a table mounted for slidable movement on said base toward and from said shaft for adjustment of said table; securing means whereby said table is secured in its various adjustments; brackets formed on one edge of said table; a disk shaft rotatably mounted in the extremities of said brackets; a worm gear secured on said disk shaft; a worm shaft rotatably mounted on said table; a worm secured on one end of said worm shaft said worm being in engagement with said worm gear; and a drive pulley secured on each one of the other ends of said grinding shaft and said worm shaft said pulleys being in alignment with each other and driven by one belt applied thereto, for simultaneously rotating said disk shaft and said grinding shaft.

In testimony whereof I affix my signature in the presence of two witnesses.

JOHN E. BRITTAINE.
